UNITED STATES PATENT OFFICE.

MELVILLE A. CLARK, OF SYRACUSE, NEW YORK.

HARP.

1,133,616.

Specification of Letters Patent. Patented Mar. 30, 1915.

Application filed January 5, 1912. Serial No. 669,573.

To all whom it may concern:

Be it known that I, MELVILLE A. CLARK, of Syracuse, in the county of Onondago, in the State of New York, have invented 5 new and useful Improvements in Harps, of which the following, taken in connection with the accompanying drawings, is a full, clear, and exact description.

This invention relates to certain improvements in harps and other string instruments, involving the use of a multiplicity of strings, covering a plurality of octaves, those of certain literal denominations, as for example the C strings, being of one color, as 10 red, while those of certain other denominations, as the F strings, are of another color, such as blue, while the remaining strings are preferably of light color, thereby facilitating the selection of the proper strings in 15 rendering a musical selection.

In the construction of harps the tuning pins pass through the neck of the harp and project some distance to opposite sides thereof, the strings being attached to the 20 pins at one side of the neck, while the angular portions, for receiving the tuning key, are disposed at the opposite side, and owing to the fact that the strings are disposed at various angles to different portions of the 25 neck and other parts of the string frame, it is not always convenient, particularly with amateurs, to locate the pin for any particular string which may require tuning.

The primary object, therefore, of my 30 present invention is to provide means whereby the tuning pin for any particular string may be more easily distinguished from the others, so as to enable the operator to expeditiously select the key for any string 35 which may require tuning with greater accuracy and therefore with less liability of error. The importance of this will be at once apparent when it is considered that in many instances during the rapid tuning of 40 the instrument, it not infrequently happens that the operator will turn the wrong key and thereby vary the pitch of a previously 45 tuned string, which of course necessitates readjustment and requires a longer time for 50 proper tuning.

In the drawings—Figure 1 is a top plan and Fig. 2 a side elevation of a portion of a harp embodying my invention.

The harp may be of any desired form and size, having a suitable neck —1— and the 55 usual strings —R—, —B— and —W—, having their lower ends attached to a suitable sounding board on the frame as —A— and their upper ends attached to corresponding tuning pins —r—, —b— and —w—. The 60 strings —R— and their corresponding tuning pins —r—, dividing the several octaves, are of one and the same color, as for example red, and in this instance represent the C strings, while another set of strings, as 65 —B— and their corresponding tuning pins —b—, throughout the several octaves, are of another color, as for example blue, and in this instance represent the F strings, while the remaining strings —W— and their corresponding tuning pins —w—, are of still 70 another or lighter color, representing the intermediate tones, and in order that the tuning pins for the strings of different pitch may be easily and quickly selected for tuning, they are made of the same color as their 75 corresponding strings. For example, the tuning pins for the C strings are all of one color, corresponding approximately to the color of their respective strings, while the 80 tuning pins for the F strings are of a color corresponding to such strings, and the tuning pins for the intermediate strings are still of another color, corresponding thereto, thereby enabling the operator to easily, 85 quickly and accurately select any one of the tuning pins corresponding to any predetermined string which may require adjustment or tuning. In like manner the bridge pins as —m— may be colored to correspond with 90 their respective strings and tuning pins and additionally facilitate the selection of the tuning pin for any string which may require tuning.

The tuning pins are usually tapered and 95 inserted in corresponding apertures through the neck —l— so as to protrude some distance to opposite sides thereof, the strings being located as usual at one side, while the angular portions for receiving the keys are 100 located at the opposite side of the neck.

By making the tuning pins of different colors, in the manner described, it is evident that the entire series are divided into octaves and that each octave is subdivided 105 into smaller groups, as for example by the

keys representing the F strings, thus enabling the operator to accurately select any pin for any particular string which may require tuning with less liability to error.

5. What I claim is:—

A harp having certain tuning pins and their corresponding strings in octave relation of one color, and certain other pins and their corresponding strings in octave rela-

tion of one color different from that of the 10 first named pins and strings.

In witness whereof I have hereunto set my hand this 27th day of December 1911.

MELVILLE A. CLARK.
